CLAIM

The ornamental design for an acetabular device, as shown and described.

DESCRIPTION

FIG. 1 is a top, left, rear perspective view of an acetabular device according to an embodiment of the new design; FIG. 2 is a front side elevation view thereof; FIG. 3 is a rear side elevation view thereof; FIG. 4 is a left side elevation view thereof; FIG. 5 is a right side elevation view thereof; FIG. 6 is a top plan view thereof; FIG. 7 is a bottom plan view thereof; FIG. 8 is a bottom, left, rear perspective view thereof; FIG. 9 is a top, left, rear perspective view of an acetabular device according to another embodiment of the new design; FIG. 10 is a front side elevation view thereof; FIG. 11 is a rear side elevation view thereof; FIG. 12 is a left side elevation view thereof; FIG. 13 is a right side elevation view thereof; FIG. 14 is a top plan view thereof; FIG. 15 is a bottom plan view thereof; and, FIG. 16 is a bottom, left, rear perspective view thereof. The broken line showing is included for the purpose of illustrating unclaimed subject matter and forms no part of the claimed design.

1 Claim, 16 Drawing Sheets
